CLAIM

The ornamental design of an insulated container for beverage bottles and cans, as shown and described.

DESCRIPTION

FIG. 1 is a top perspective view of the insulated container for beverage bottles and cans showing my new design.

FIG. 2 is a bottom perspective view thereof.

FIG. 3 is a right side view thereof.

FIG. 4 is a left side view thereof.

FIG. 5 is a front view thereof.

FIG. 6 is a rear view thereof.

FIG. 7 is a top plan view thereof.

FIG. 8 is a bottom plan view thereof.

FIG. 9 is an exploded perspective view thereof, the beverage bottle is shown in broken lines and forms no part of the claimed design.

FIG. 10 is an exploded perspective view thereof, the beverage can is shown in broken lines and forms no part of the claimed design; and,

FIG. 11 is an exploded view thereof.
